UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,337,115.

Specification of Letters Patent.

Patented Apr. 13, 1920.

Application filed November 27, 1917. Serial No. 204,251.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention relates to improvements in separable fasteners, and more particularly, though not exclusively, to stud and socket fasteners wherein a stud having an expandable head is adapted to coöperate with a socket having an aperture of fixed dimensions, said stud being separable from said socket by relative tipping movement in one direction only.

Referring to the drawings:

Figure 1 is a front elevation of a preferred form of fastener constituting one embodiment of my invention;

Fig. 2 is a section thereof, partly in elevation, on the line 2—2 of Fig. 1; and

Fig. 3 is a section, partly in elevation, on the line 3—3 of Fig. 2.

I have elected to show my invention in connection with the securing of a curtain to the body of an automobile, and in the drawings I have shown the socket as a round hole in the sheet metal side 4 of the body of the car, and I have shown the stud attached to an automobile curtain 5. In the preferred form of my invention selected for illustrative purposes, I have shown the stud having a head portion 6, preferably pressed from sheet metal and split longitudinally thereof to receive the resilient wire 7, which is preferably, as shown, provided with two coils adapted to project on opposite sides of the head 6 and to engage the sides 8 of the aperture forming the socket. The preferred form of double coil shown in the drawings is peculiarly desirable because the strain on the wire is well distributed, and because one of the coils provides a squared shoulder 9 for engagement with the edge of the socket opening, while the other coil provides a rounded portion for engagement with the opposite edge of said socket opening, thus affording a very simple and inexpensive form of "one-way fastener". In the embodiment of my invention shown in the drawings, the head 6 is provided with an annular flange 10 adapted to engage a flange 11 having a tubular projection 12 adapted to pass through the curtain 5 and to be riveted over a plate 13 on the opposite side of the curtain. The ends of the resilient wire forming the expandable portions of the head are preferably held between the flanges 10 and 11, while being positioned laterally by the sides of the slot in the head 6 through which the socket-engaging portions of said wire project. To facilitate ready separation of the stud from the socket by tipping movement, I have shown the flanges 10 and 11 projecting downwardly away from the squared jaw 9 a considerable distance farther than the opposite sides of said flanges project in a direction toward said jaw 9. This permits the flange 10 to closely abut against the face of the socket, while permitting the stud to rock about the squared jaw 9 when separation of the stud from the socket is to be effected. When the stud is to be entered in the socket, the loops in the resilient portion of the stud yield when pressed against the sides of the aperture forming the socket, thus permitting the stud to enter the socket, after which they immediately spring outwardly to engage the sides of the aperture interiorly of the socket and to strongly resist separation of stud and socket. Separation of stud and socket may, however, be readily effected by an outward pull on the bottom of the curtain 5, which rocks the stud about the squared jaw 9, the rounded spring jaw yielding until such position is reached that the stud has no further tendency to remain in the socket. If, however, force be exerted on the upper portion of the curtain 5, as by the wind, or by an occupant of the car leaning against the curtain, such pressure will not open the socket because the squared jaw 9 will be firmly and squarely engaged by the coöperating interior edge or wall of the socket aperture. Similarly, lateral relative tipping movement of stud and socket will be ineffective to disengage the squared jaw 9 from the coöperating portion of the socket.

While I have shown and described one embodiment of my invention, it will be understood that changes involving omission, alteration, substitution and reversal of parts, and even changes in the mode of operation,

may be made without departing from the scope of my invention, which is best defined in the following claims.

Claims:

5. 1. A stud and socket fastener comprising, in combination, a socket, and a stud having a head comprising a shell and opposed expandible resilient elements projecting through said shell, one of said elements presenting an abrupt shoulder to a coöperating portion of said socket, and the other of said elements presenting a rounded portion to a coöperating portion of said socket.
10. 2. A stud and socket fastener comprising, in combination, a socket, a stud having a slotted head portion carrying a double coil of wire presenting opposed resilient socket-engaging portions, one of said coils presenting an abrupt shoulder for engagement with a coöperating portion of said socket, and the other of said coils presenting a rounded shoulder for engagement with a coöperating portion of said socket.
15. 3. A stud and socket fastener comprising, in combination, a socket, and a stud having a head portion of fixed proportions having a slot therein and a coiled wire projecting through said slot for engagement with the socket, one side of said wire presenting an abrupt shoulder for engagement with the socket and the other side thereof presenting a rounded shoulder for engagement with the socket.
20. 4. A stud and socket fastener comprising, in combination, a socket, and a stud having a head portion presenting opposite resilient elements, both of said elements yielding when the stud is entered in the socket, while only one of said elements is free to yield when said stud is withdrawn from said socket.
25. 5. A stud and socket fastener comprising, in combination, a socket providing an aperture, and a stud having an expandible head comprising a casing and a resilient element carried thereby for engagement in said aperture, said head being separable from said socket by tipping movement in one direction only and being inseparable therefrom by outward strain in a direction axial of the stud.
30. 6. A stud and socket fastener comprising, in combination, a socket providing an aperture, and a stud having an expandible head for engagement in said aperture, said head being separable from said socket by tipping movement in one direction only, being inseparable therefrom by outward strain in a direction axial of the stud, and said stud being engageable with said socket by rectilinear movement into said socket.
35. 7. A stud and socket fastener comprising, in combination, a socket, a stud comprising a hollow head, resilient elements terminally supported in said head and carrying inwardly yieldable engaging portions projecting through said head, one such portion having an inner abrupt shoulder and the other a shoulder tapered inwardly.

In testimony whereof, I have signed my name to this specification.

FRED S. CARR.
